FENCE CONNECTING MEANS

Carl A. Phipps, Sioux Rapids, Iowa

Application March 29, 1937, Serial No. 133,603

10 Claims. (CL. 256—1)

An object of my invention is to provide a fence connecting means of simple, durable and inexpensive construction.

A further object is to provide means for connecting two sections of a fence together, my connecting means being especially adaptable for slat fences, and particularly desirable for use in connection with "snow fences".

Still a further object is to provide a connecting means which is readily operable to connect or disconnect the ends of two sections of fence relative to each other, the connecting means being thereby a matter of convenience for the purpose of connecting snow fence sections together when the fence is erected in the fall and for quickly disconnecting them when it is taken down in the spring.

Still a further object is to provide hooks of a predetermined shape which are so associated with the adjacent ends of two sections of a fence that three of them can be used, and adjacent ones arranged to contact with opposite sides of the end slats of the fence in such manner that two of them can be loosely placed in position, and when the third one is placed in position, the ends of the fence are effectively connected against any accidental disconnection, the connecting means, however, permitting ready disassociation of the fence ends when one of the connecting hooks is removed.

With these and other objects in view, my invention consists in the construction, arrangement and combination of the various parts of the device, whereby the objects contemplated are attained, as hereinafter more fully set forth, pointed out in my claims, and illustrated in the accompanying drawing, in which:

Figure 1 is a perspective view of a fence connecting hook embodying my invention.

Figure 2 is a front elevation of a fence showing how three of the hooks of Figure 1 are associated therewith to connect two sections of the fence together.

Figure 3 is a sectional view on the line 3—3 of Figure 2 showing the upper hook removed and the end slats of the fence adjusted to a position where the lower two hooks will readily drop off the fence.

Figure 4 is an enlarged plan view of the end slats of two adjacent fence sections showing my fastening means associated therewith; and

Figure 5 is a sectional view on the line 5—5 of Figure 4.

On the accompanying drawing I have used the reference character H to indicate generally a

hook which is of predetermined shape, and provides a means for connecting fence sections together. The hook H has a pair of body portions 10 and 10' which are preferably offset relative to each other and connected by a diagonal connecting part 12.

The ends of the body portions 10 and 10' terminate in hooks 14 and 14' respectively. These hooks extend in directions opposite the direction of the offset of their adjacent body portions, and open in the same direction as the direction of the offset. The hook 14' is preferably closed more than the hook 14, as best shown in Figure 5, and the hook 14 may have its terminal end somewhat lengthened to provide better connection with the tie wire of a fence.

In Figures 2, 3 and 4 a pair of fence sections F and F' are illustrated, the end slats of which are indicated at 16 and 16'. The slats are tied together in the usual manner by tie wires 18. The hooks H are associated with the slats 16 and 16' as shown in Figures 2 and 4.

Referring to Figure 4, it will be noted that the body portion 10 engages one side of the slat 16, while the body portion 10' engages the opposite side of the slat 16'. This is true of all three of the hooks H, H' and H''.

The hook H' it will be noted is turned over relative to the hook H so that the body portion 10 thereof extends around opposite sides of the slat 16 relative to the body portion 10' of the hook H. Likewise the body portions 10 and 10' of the hook H'' coincide with those of the hook H and are reversed relative to those of the hook H'.

In order to hook the hook H on the fence, the hook portion 14' thereof is first hooked over the tie wire at the right of Figure 4. This hook being more closed than the hook 14 will engage at the twist of the tie wire as shown in the right half of Figure 5. The slats 16 and 16' and the hook H are then manipulated relative to each other so that the body portions 10' and 10 extend around opposite sides of the slats 16' and 16, and thereafter the tie wire at the left of Figure 4 is swung from the dotted line position to the full line position within the hook 14. The fastener H is now in its final position and holds the slats 16 and 16' against any possible movement out of alignment with each other.

When the fence sections are to be disconnected after the hook H is removed, the slats 16 and 16' can be spread as shown in Figure 3, which loosens the hooks H' and H'', so that they will either fall off or can be readily taken off. Likewise in the connecting of the fence sections together, the

slats 13 and 16' may be caused to assume the position shown in Figure 3, whereupon the hooks H' and H'' can be placed in position, the slats alined with each other and then the hook H placed in position.

5 Connection of the fence sections together by my fastener is thus accomplished in a minimum of time, and eliminates the undesirable expedient now in general use of wiring the fence sections 10 together. Such wires are usually left in the field which is objected to by the farmer, and are usable but once. Hooks of the character disclosed, however, can be used many times, and save both time and expense, and are therefore a great convenience.

15 Some changes may be made in the construction and arrangement of the parts of my device without departing from the real spirit and purpose of my invention, and it is my intention to 20 cover by my claims any modified forms of structure or use of mechanical equivalents which may be reasonably included within their scope.

I claim as my invention:

1. In a fence connecting means for a slat fence, 25 a plurality of hooks each having a pair of offset body portions contacting with opposite sides of two end slats of a pair of fence sections, each body portion terminating in a hook for engagement with the tie wire of one of the fence sections, 30 said hooks opening in opposite directions, one of said hooks being closed sufficiently to tightly engage the tie wire, said hooks being vertically spaced along the slats of the fence sections and adjacent ones thereof being arranged with the 35 body portions thereof along the slat offset in opposite directions.

2. In a fence connecting means for a slat fence, a plurality of hooks each having a pair of offset body portions contacting with opposite sides 40 of two end slats of a pair of fence sections, each body portion terminating in a hook for engagement with the tie wire of one of the fence sections, one of said hooks being closed sufficiently to tightly engage the tie wire, said hooks being 45 vertically spaced along the slats of the fence sections and adjacent ones thereof being arranged with the body portions thereof along the slat offset in opposite directions.

3. In a fence connecting means for a slat fence, 50 a plurality of hooks each having a pair of offset body portions contacting with opposite sides of two end slats of a pair of fence sections, each body portion terminating in a hook for engagement with the tie wire of one of the fence sections, said hooks opening in opposite directions, 55 said hooks being vertically spaced along the slats of the fence sections and adjacent ones thereof

being arranged with the body portions thereof along the slat offset in opposite directions.

4. In a fence connecting means for a slat fence, a plurality of hooks each having a pair of offset body portions contacting with opposite sides of two end slats of a pair of fence sections, each body portion terminating in a hook for engagement with the tie wire of one of the fence sections, said hooks being vertically spaced along the slats of the fence sections and adjacent ones thereof being arranged with the body portions thereof along the slat offset in opposite directions. 10

5. In a fence connecting means for a slat fence, a plurality of hooks each having a pair of offset body portions contacting with opposite sides of two end slats of a pair of fence sections, each body portion terminating in a hook for engagement with the tie wire of one of the fence sections, said hooks being vertically spaced along 15 the slats of the fence sections.

6. In a fence connecting means for a slat fence, a plurality of hooks, each having a pair of offset body portions contacting with opposite sides of two end slats of a pair of fence sections, each body portion terminating in a hook for engagement with the tie wire of one of the fence sections, said hooks opening in opposite directions, 20 said hooks being vertically spaced along the slats of the fence sections.

7. Fence connecting means comprising an elongated element having a pair of body portions offset relative to each other and terminating in hooks which extend in directions opposite the direction of the offset of the body portions. 30

8. Fence connecting means comprising a length of wire having a pair of offset body portions, a connecting portion extending diagonally between said body portions and a pair of hooks at the terminal ends of said body portions. 40

9. Fence connecting means comprising a length of wire having a pair of offset body portions, a connecting portion extending between said body portions and a pair of hooks at the terminal ends of said body portions, said hooks opening in directions opposite the direction of offset of their adjacent body portions. 45

10. Fence connecting means comprising a length of wire having a pair of offset body portions, a connecting portion extending between said body portions and a pair of hooks at the terminal ends of said body portions, said hooks opening in directions opposite the direction of offset of their adjacent body portions and one thereof being more closed than the other thereof. 50 55
